UNITED STATES PATENT OFFICE.

KENNEDY DOUGAN, OF MINNEAPOLIS, MINNESOTA.

INTERNAL-COMBUSTION ENGINE.

1,216,965.

Specification of Letters Patent. Patented Feb. 20, 1917.

Application filed October 2, 1911. Serial No. 652,379.

To all whom it may concern:

Be it known that I, KENNEDY DOUGAN, a citizen of the United States, residing at Minneapolis, in the county of Hennepin and 5 State of Minnesota, have invented certain new and useful Improvements in Internal-Combustion Engines, of which the following is a specification.

My invention relates to internal combustion engines of the type shown and described in my applications, Serial Numbers 10 635,206, filed June 24, 1911, and 647,175, filed September 1, 1911, in which the force of the explosion within the combustion 15 chamber operates to raise a weight, the energy thereby accumulated being used to perform useful work when the weight falls. My present invention relates to an explosive engine of this type in which the engine 20 unit is of a two-cycle operating type, and is connected to a weight-operating member and combined with a pump the piston of which is also connected to the weight-operating member. An important feature of 25 the invention consists in the combination of means for operating the valves of a two-cycle engine positively and in timed relation.

It is one of the principal objects of my 30 invention to provide an engine cylinder having an exhaust port, a scavenger intake port and a charging port combined with means for positively opening said ports in rapid succession with a suitable retard in 35 the opening of the charging port followed by closing all of said ports practically simultaneously, these means operating with equal effect when the scavenging device is omitted, which is contemplated in some 40 uses to which my invention is designed to be put. Means are also provided whereby air is caused to be stored under pressure in a receptacle connected with the scavenger port, if a scavenging device is used, during 45 the descending movement of the weight-operating member and at the same time a fuel charge is drawn from a suitable carburetor mechanism into a fuel storage chamber, which charge will be compressed on the 50 return movement of the weight-operating member and forced under pressure into the engine cylinder when the charging port is uncovered.

A further object of my invention is to 55 provide a rotating valve closure for covering all of said ports and for opening the

same in suitably timed succession combined with means under the control of the fluid compressed by the pump for rotating said valve in the proper cycle of engine action, 60 this valve closure being adapted for combination with means for cooling the same and thereby cooling the interior of the engine cylinder. It is a further object of my invention to provide said cooling means in 65 combination with the aforesaid valve closure.

It is a further object of my invention to provide in combination with the aforesaid exhaust scavenger intake and fuel intake 70 ports, a series of valves in combination with mechanical means for successively operating the same in properly timed relation.

It is a further object of my invention to provide in combination with the weight- 75 operating member aforesaid a single pump piston combined with mechanism whereby said pump may be operated either as a hydraulic pump or an air pump.

A further object of my invention is to 80 provide in combination with the aforesaid weight-operating member and pump a device controlled by the condition of the fluid in the storage tank for automatically stopping action of the pump when such condition reaches a predetermined degree and for automatically restarting the pump when the condition falls below a predetermined degree. 85

A further object of my invention is to 90 provide a sparking device operative through upward movement of the weight-operating member and adjustable so that the sparking action may take place at exactly the proper point in the return movement of the engine 95 cylinder after compression of the charge therein has been effected.

Other objects and advantages of my invention will appear in the detailed description thereof, and are particularly pointed 100 out in the claims.

In the drawings,—

Figure 1 is a sectional elevation view of one form of my invention. Fig. 2 is a side elevation thereof with parts omitted. Fig. 105 2^a is a detail in vertical section taken approximately on the line 2^a 2^a of Fig. 2. Fig. 3 is a sectional plan taken on line 3—3 of Fig. 1. Fig. 4 is a section on line 4—4 of Fig. 1. Fig. 5 is a top end view of the rotary valve closure. Fig. 6 is a sectional elevation of a part of the engine in which no 110

scavenging device is used. Fig. 7 is a section on line 7—7 of Fig. 6. Fig. 8 is a sectional elevation of a modified form of my invention including the interchangeable pump, the improved sparking device and the automatic stopping and starting mechanism. Fig. 9 is a section on line 9—9 of Fig. 8. Fig. 8^a is a fragmentary section on the line 8^a 8^a of Fig. 8. Fig. 10 is a diagrammatic view showing the shapes and relative positions of the valve operating cams. Fig. 11 is a detail of one means for driving the valve-operating cam shaft. Fig. 12 is a detail view of another means for operating said cam shaft. Fig. 13 is a sectional elevation taken at right angles to the showing of Fig. 8 with some parts omitted. Fig. 14 is a section on line 14—14 of Fig. 8 viewed downwardly. Fig. 15 is a sectional plan on the same section line viewed upwardly. Fig. 16 is a top plan view of the charging cylinders.

Side frame members 20 and 21 are provided between which is secured the cylinder 22 of an explosive engine, the piston 23 of which is connected by piston rod 24 with a weight-operating member 25 carrying a weight 26 and secured to the piston rod 27 of a pump piston 28 working in a pump cylinder 29 of the type described in my applications above identified. As shown in Fig. 8, the pump cylinder 29 is adapted to be used either as a hydraulic pump or an air pump. To this end two outlet pipes 30 and 31 are provided, pipe 30 leading to a storage tank for compressed air and pipe 31 leading to a storage tank for water. A gate valve 32 is provided for closing pipe 30 when the pump is used for pumping water. Set screws 33 are adapted to be screwed down upon outlet valves 34 to close outlet pipe 31 when the pump is used for pumping air, an air inlet valve 35 located at the top of the chamber 36 above the line of highest water level in the cylinder 29 permitting inflow of air which is forced through valve 37 into the compression tank by the rise of a column of water in chamber 36 when piston 28 descends, the fall of said column of water when piston 28 rises operating to create the vacuum which causes air to enter through valve 35.

Cylinder 22 is provided in the bottom thereof with three ports, 38, 39 and 40, respectively, of the shape and arrangement shown in Fig. 4, or three ports 41, 42 and 43 of the shape and arrangement shown in Fig. 9. In the structure shown in Figs. 1 and 4, the ports 38, 39 and 40 are adapted to be closed by an oscillating valve closure 44, of a plan outline shown in Fig. 5, which may have the cross-sectional form shown in Fig. 1, providing a chamber 45 suitable for use in cooling the piston and through that cooling the cylinder. To that end the valve

closure 44 is provided with a hollow cylindrical stem 46 which is rotatably mounted in a tubular bearing 47 carried by the frame. A cup-shaped member 48 is carried by the frame below member 46 and is provided with a threaded opening 49 and a waste cock 50. A water supply pipe 51 is threaded into the lower end of opening 49 and another pipe 52 is threaded into said opening above and spaced from the end of pipe 51, pipe 52 extending through the center of tubular stem 46 and into a steadyng tubular member 53 depending from valve closure 44 within chamber 45, said steadyng member 53 being provided with apertures 54 through which water conveyed through pipe 52 may spray upon the inner walls of chamber 45. Rigidly secured upon pipe 52 is a collar 55 which is adapted to form a closure for the bottom of tubular stem 46 by which the rate of flow of water through the valve closure may be regulated, the water flowing over collar 55 and down pipe 52 into cup-shaped member 48 and from there out of waste cock 50 from which it is conveyed to any desired point. A ring piece 56 is secured to member 48 and engaged by set screw 57 threaded into a member 58 secured to collar 55. In Fig. 1, the stem of 58 is shown as rigidly inserted into a radial sleeve of the collar 55, and which sleeve is shown in section. By loosening set screw 57 pipe 52 may, through member 58, be rotated, which, by reason of the threading of the same into opening 49, will cause the collar 55 to approach or recede from the end of tubular stem 46 to regulate the rate of flow of water through chamber 45.

Port 38 is connected with exhaust pipe 59. Port 39 is connected with pipe 60 leading from a chamber 61 in which air is compressed for scavenging purposes by means of a piston 62 working in a cylinder 63 and connected by means of rod 64 with weight-operating member 25. An intake valve 65 and apertures 66 into cylinder 63 are provided whereby when piston 62 rises said cylinder will be filled with air. When the piston falls this air will be driven through outlet valve 67 into chamber 61 from which it may enter engine cylinder 22 through port 39 when said port is opened by operation of valve closure 44. This pure air entering the engine cylinder under pressure will drive out the remaining combustion gases therein, completing exhaust in time for the reception of the fuel charge from the charging valve 40. This valve is connected by means of pipe 68 with a charging chamber 69, valve 70 connecting pipe 68 with carburetor mechanism of known construction, not shown. A series of apertures 71 open from chamber 69 into cylinder 63, said apertures being located far enough

from the top wall of cylinder 63 so that when piston 62 is in its highest position said piston will cover apertures 71 providing an air cushion above piston 62 to check the upward stroke of the engine should the explosive charge be large enough to require such checking. A similar arrangement of the aperture 66 near the bottom wall of cylinder 63 provides air cushioning means to check the downward stroke if for any cause the exhaust port should fail to be closed at the proper time. It will be noted that when piston 62 descends explosive mixture from the carburetor will be drawn into chamber 69 through valve 70 and pipe 68, and when piston 62 rises this charge will be compressed so that the same will flow under pressure into cylinder 22 when charging port 40 is uncovered in the proper cycle of the operation of the machine. By filling chamber 69 to a greater or less degree with water, the compression of the charge may be correspondingly varied.

The valve closure 44 is oscillated a semi-revolution forward and back at each downward stroke of engine piston 23, and this operation of the valve is effected through the pressure of the fluid in the pump cylinder by the following means. An auxiliary cylinder 72 is provided, the base of which is surrounded by an enlarged cylindrical chamber 73 in communication with the main pumping cylinder 29 and communicating with the interior of cylinder 72 by means of a row of ports 74 adjacent the top of cylinder 73 and a single port 75 opening through the side of said cylinder 72 and adapted to be closed, as desired, by a choke valve 76. A piston 77 works in cylinder 72 and has depending therefrom a rod 78 connected with a hollow piston ring 79, the piston 77 and piston ring 79 being spaced so that when said piston ring 79 is in its lowered position resting upon the floor of cylinder 72 piston 77 will occupy a position just above the ring of ports 74. A rack bar 80 is connected with piston 77 and is formed to slide within cylinder 72 so that the teeth 83 thereof will engage a pinion 84 loose on a shaft 85 journaled in brackets 86, 87 secured to cylinders 72 and 29, respectively. The shaft 85 has fast thereon a ratchet wheel 88 and a crank disk 89, the ratchet wheel 88 being engaged by a ratchet 90 on a radial arm 84 carried by pinion 84, so that when rack member 80 moves up rotation of pinion 84 will be communicated to shaft 85 through ratchet 90 and ratchet wheel 88, while return movement will be effected without operating shaft 85. Crank disk 89 has thereon a pin 91 operating in a slot 92 in an arm 93 of a lever centrally pivoted at 94 to a bracket 95 carried by a frame member. The upper end 96 of said pivot lever is provided with a rack segment

97 in mesh with a bevel pinion 98 fast on the lower end of tubular valve stem 46. As pump piston 28 starts to descend pressure will be communicated to piston 77 in cylinder 72 and the same will be forced upward, 70 since the piston ring 79 being hollow or tubular permits said ring to rise unchecked by the pressure of the water in cylinder 72. The effect of this upward movement is to rotate crank disk 89 and, through pin 91 75 engaging in slot 92, rock lever arm 96, by means of which rack segment 97 rotates valve closure 44 to uncover successively exhaust port 38 and scavenger port 39. The upward movement of piston 77 necessary 80 to effect this result will bring piston ring 79 opposite the ring of ports 74 with the result that pressure will be cut off from that source, but liquid still may flow through port 75, at a reduced rate, however, which 85 is determined by the degree of closure effected by choke valve 76. This results in retarding the movement of valve closure 44 during the opening of charging port 40 to permit completion of exhaust and scavenging of the engine cylinder. When the piston ring 79 has passed beyond ports 74 piston 77 will continue its rapid rise completing opening of charging port 40 and thereafter, by reason of return movement of 95 pin 91 operating in slot 92, will return lever 96 to initial position, closing in quick succession all of the valves.

It is noted that the pinion 84 is of such size and the movement of rack 80 in mesh 100 therewith by piston 77 is of such extent, that the full stroke of said piston and rack will rotate the pinion 84 a full turn, thus taking the pin 91 from its outward or normal position to the extreme inward position, and 105 immediately returning it again to said outward position. This movement effects the valve operations through lever 96 and connections, as above described.

Figs. 6 and 7 show the application of the 110 above described valve operating means to an engine cylinder provided with exhaust and charging ports only. In this structure a fuel mixture chamber 99 is provided, connected through intermediate chamber 100 115 and valves 101 and 102 with carburetor mechanism, not shown, said chamber 100 opening into cylinder 22 through a series of ports 103 similar in position and function to ports 71 in cylinder 63. This arrangement is such that downward movement of piston 23 will draw into cylinder 22 through ports 103 the fuel mixture, return movement of said piston forcing said mixture through valve 102 into storage chamber 99 120 from which it will flow under pressure through port 40 when the same is opened by operation of a specially constructed valve closure 104 operated by means similar to the means for operating valve closure 44. 125 130

The valve closure 104 is provided with oppositely positioned closing members 105, 106 with an intervening open portion 107, the portion 106 being double the width of the portion 105 and operating above fuel intake port 40. The oscillation of valve closure 104 is of less extent than that of valve closure 44, being but little more than a quarter revolution each way, and results first in uncovering exhaust port 38, charging port 40 remaining covered by reason of the greater width of the portion 106. Retarding takes place in this form of valve closure as in the other form just before opening of charging port 40. To prevent possible damage from return movement of the weight-operating member in case exhaust valve 38 should fail to be closed at the proper time, cylinder 22 may be provided with a flanged rim 108 forming a cylindrical air cushioning space 109 with which a disk 110 surrounding piston rod 24 below a cross bar of weight-operating member 25 would coöperate should the descending piston fail to be properly checked by compression of a charge within cylinder 22.

In the form of my device shown in Figs. 8 and 13, exhaust port 41 is provided with a stem valve 111, scavenger port 42 with a stem valve 112, and charging port 43 with a stem valve 113. Port 41 opens into an exhaust pipe 114, scavenger port 42 opens into a pipe 115 leading to a storage chamber 116 in which air is compressed through operation of the upper portion of piston 23 by means of intake valve 117 and outlet valve 118. Charging port 43 is connected by means of pipe 119 with a fuel storage chamber 120. The fuel mixture is forced under pressure into chamber 120 by means of a piston 121 operating in a cylinder 122 above engine cylinder 22 and connected with weight-operating member 25 by means of piston rod 123, the interior of cylinder 122 being connected by means of a series of ports 124 with an intermediate chamber 125 having valve connection 126 with carburetor mechanism, not shown, and valve connection 127 with interior of chamber 120. Valves 111, 112 and 113 are pivoted to levers 128, 129 and 130, respectively, which levers operate through slots in frame member 20, and are pivoted at their outer ends to brackets 131, 132 and 133, respectively, said brackets being of such length relative to frame member 20 that the distance between the points of pivoting to said brackets and to the valve stems will be equal in each lever. Journaled in cross pieces 134 and 135 is a cam shaft 136 provided with a series of cams 137, 138 and 139. The shape and relative positions thereof on the cam shaft is diagrammatically indicated in Fig. 10, the positions there shown indicating the normal or inoperative position in which the faces of the cams are

all horizontal and in parallel relation with the valve levers 128, 129 and 130, respectively, but spaced therefrom slightly, as indicated in Fig. 13, said valve levers being held in their lowered positions to close the valves by means of springs 140. It will be noted that the high or active portions of the cams 137, 138 and 139 are so formed and related to one another that when cam shaft 136 is rotated it will operate first to lift exhaust valve 111 and immediately thereafter will lift scavenger valve 112, but will not lift fuel intake valve 113 until near the end of its semi-revolution with the result that opening of the charging valve is retarded relatively to opening of the other valves.

The cam shaft 136 has fast thereon a ratchet wheel 141, and is also provided with a pinion 142 loose on said shaft and having a ratchet tooth 143 engaging the ratchet wheel 141. Secured to yoke-operating member 25 is a rack 144 the teeth of which mesh with the teeth of pinion 142. As shown in Fig. 11, gear 142 is mutilated or segmental, and a pin 151 or 151', in either position, is engaged by a spring 145 which retains the gear in position to certainly engage rack teeth 144 at the moment of the starting of movement thereof in either direction. It is necessary to employ a structure of this sort since the stroke of weight-operating member 25 and rack 144 will vary while the cam shaft 136 must always be rotated a half revolution. For this reason ratchet wheel 141 is provided with but two diametrically opposite ratchet teeth 146 and 147 which are adapted to oscillate backwardly when ratchet arm 143 moves backwardly to permit the same to pass said teeth but which will be held in the path of said ratchet arm so that the same will rotate the ratchet disk 141 and cam shaft 136 when pinion 142 swings ratchet arm 143 in the opposite direction during descending movement of rack 144.

Fig. 12 represents a friction device for accomplishing the same purpose, in which a friction surface 148 takes the place of rack 144 and a friction wheel 149 of pinion 142, the friction wheel being cut away, as shown at 150, and the spring 145 engaging pins 151, 151' on said friction wheel to hold the same in active engagement with friction surface 148. The friction surface member 148 may be connected by spring means to a back plate 152 having set screws 153 and 154 for positioning the friction member 148 so as to provide the most effective possible working surface. As shown, the curved surface of wheel 149 may have slight eccentricity.

It will be understood that the work accomplished by my engine may be varied by varying the proportion of fuel and air in the explosive mixture supplied to the engine cylinder, this variation being effected by well

known means in the carburetor mechanism. It is true, however, that in any event the stroke of such an engine will vary, since it is connected with no crank axle or other part 5 having a determinate movement. Since exhaust and charging both taking place during the descending stroke of the piston, the point at which the compressed charge in the cylinder will terminate the down-stroke will 10 vary materially, as well as the point of termination of the up-stroke brought about by variation in the explosive power in the force exerted by the explosion of different charges. Sparking, however, should take 15 place at the point of termination of the descending stroke or preferably after the expansion of the compressed charge has reacted to begin the return of the parts. For producing this sparking action, properly 20 timed, I have arranged a contact 155 in the circuit of the ignition system, the same being mounted upon a bracket 156 secured to the frame members, said contact being adjustably held on bracket 156 by means of a 25 bolt 157 engaging in a slot 158 in the contact bracket 155. A lever 159 is provided at the free end thereof with a contact member 160 adapted to contact with contact member 158 and close the circuit for producing 30 an ignition spark, the lower end of said lever being fast on a shaft 261 extending between brackets 162 and 162' extended from frame members 20 and 21. The shaft 261 has fast thereon a collar 262 adjacent the 35 head 263 of lever 159, a similar collar, 264, being secured to shaft 261 near the bearing thereof in bracket 162'. Loose on shaft 261 is a friction wheel 161, one face of which abuts the base plate 263 of arm 159, the 40 other face normally contacting with a friction plate 265 loose on shaft 261 and pressed against friction wheel 161 by a coil spring 161' surrounding shaft 261 and extending between collar 264 on said shaft and a tubular 45 extension 266 fast on plate 265. All of the force of spring 161', therefore, is exerted in frictionally clamping roller 161 between friction plate 265 and base plate 263. Friction plate 265 is provided with a finger 50 267 extending freely through an aperture in an extended portion 168 of base plate 263, so that friction plate will be free to move laterally on the shaft 261, but will be constrained to rotate with said shaft and the 55 arm 159 carried thereby. The friction wheel 159 is engaged and rotated by a friction bar 163 pivoted at 164 to weight operating member 25 and additionally secured to said member by a pin 165 extending through 60 a slot 166 in friction plate 163, a spring 167 engaging the lower end of said plate and resiliently pressing the same against the friction wheel 161. The projection 168 on the base plate 263 is arranged to engage an 65 arm 168' extending from bracket arm 162,

limiting the movement of lever arm 159 in an outward direction during the downward stroke of the weight-operating member. When, however, said member starts to ascend coaction of the friction surfaces and friction wheel 161 will rock the lever arm 159 bringing contact 160 into conjunction with contact 155 to close a circuit and effect 70 sparking action. By adjusting the fixed contact member 155 inwardly or outwardly 75 the exact point in the re-bound or return stroke of the engine at which sparking shall be effected can be regulated with the utmost nicety.

When my engine is used for pumping it 80 will be desirable to provide means for automatically stopping and restarting action thereof in accordance with the condition or quantity of fluid in the storage tank connected with the pump, for which purpose I 85 have devised the following means. Secured to a storage tank 169 for receiving the fluid from the pump is a bracket arm 170 upon which is centrally pivoted a lever 171 pivotally connected at one end with a float 172 90 and at the other end with a link 173, said link being pivotally connected with an arm 174 and a lever pivoted at 175 to a bracket 176. A rocking member 177 is pivoted at 178 to a lower corner of the weight-operating member 25, said rocking member comprising a horizontally extended portion 179 and a vertical member 180 for engaging weight-operating member 25 to limit the 95 rocking movement of member 177 in one 100 direction. The vertical arm of the member 180 is channel-shaped in cross section and closely engages the member 14 so that it acts as a cushion to prevent pounding. Horizontally extended member 179 is pivotally 105 connected with a link 181 which in turn is pivoted at its end to a link 182 pivoted at 183 to a fixed member, link 183 having a foot portion 184 engaged by a spring 185 tending to press the upper end of link 182 against the rounded end 186 of a short arm 187 extending out from pivot 175 of lever 174. The combined length of links 181 and 182 is such that a minimum upward stroke of 110 the weight-operating member will extend them into a common line, any excess of stroke thereover rocking member 177 against the pressure of a spring 188 provided for normally holding member 180 in contact with weight-operating member 25. When 115 the level of the water in tank 169 is below a certain point, descent of float 172 through connecting parts will position lever 187 so as to break the joint between links 181 and 182 inwardly, which will permit jack-knifing of 120 said links and continuous operation of the machine. But when the level of the contents of the tank rises to a predetermined point the head 186 will be drawn back so that the 125 said joint, held in engagement therewith at 130

the up-stroke by spring 185 acting on foot 184, will be broken outwardly so that links 181 and 182 will thereby automatically act to hold weight-operating member in its raised position and suspend action of the engine until the said level again falls.

When rack 80, operated by piston 77 through the pressure of the fluid in the pumping cylinder, is used to actuate the valve closure 44, as shown in Fig. 1, it may be necessary, when there is little or no back pressure in the pump by reason of the container being empty, or pumping taking place through an open pipe, as in the case of irrigating pumps, that means shall be provided to create such a pressure within the cylinder at the commencement of the stroke thereof as will insure operation of piston 77. To accomplish this end I provide in an outlet pipe 190 of the pump, high outlet valves 191, a special valve port 192 in a partition 193, extending across outlet pipe 190 and separating it from a chamber 194 formed in the course of outlet pipe 190. Chamber 194 is provided with an up-standing member 195 upon which is secured a bracket 196 and to this bracket a lever 197 is centrally fulcrumed, a link 198 being pivotally connected to one arm of said lever and a link 199 being pivotally connected to the other arm of said lever. Pivotally connected to link 198 is a closure 200 covering ports 192. Chamber 194 is formed with a cylindrical portion 201 in which operates a piston 202 pivotally connected to link 199, piston 202 being actuated by a powerful coil spring 203 to rock lever 197 in a direction to force closure 200 down upon port 192, the pressure exerted by spring 203 being subject to regulation by means of a set screw 204 threaded into the bottom wall of cylinder 201 and engaging a socket plate 205 which forms the support for one end of spring 203. By operating said screw 204, the operation of spring 203 may be varied, resulting in increasing or decreasing the force exerted upon closure 200. In order that this mechanism shall operate with certainty and with sufficient quickness, it is necessary that piston 202 shall move freely in cylinder 201 and, to effect this, a joint which is not strictly air or water tight must be used. Some leakage therefore will take place and to permit escape of the fluid so leaking, a port 206 is provided in the bottom wall of cylinder 201, said port being closed by a block 207 on the end of a rod 208 secured to piston 202 and sliding through plate 205. The area of piston 202 will be considerably greater than that of port 193, the ratio being two to one, or more or less, as desired. In operation, therefore, pressure generated by pumping piston 28 may overcome the pressure of spring 203 and lift valve 200, when such pressure is greater than that exerted by special spring. If, however,

the pressure in the container connected with outlet pipe 190 rises above a certain point, such pressure exerted upon piston 202, being greater than the whole force of spring 203 plus the pressure exerted upon closure 200, will force said piston downward, holding valve 200 up so as to open port 192 and forcing block 207 into vent 206 to close said vent. This device therefore will operate to increase pressure in the pumping cylinder only until the back pressure therein, due to pressure in the container of the pump, falls below a predetermined point.

The operation of my device has been fully given in connection with the detailed description thereof and will be readily understood. The engine, which is primarily intended for pumping purposes, is simple in construction and wholly efficient in operation. It will be obvious, however, that various modifications in form and use may be contrived which fall within the scope of my invention and I do not desire to limit myself to the precise structure or arrangement of parts shown and described.

I claim:

1. In combination, a weight and an explosive engine having the piston thereof connected to the weight and adapted to lift the same through variable distances, the cylinder of said engine being provided with an exhaust port and a charging port, means for delivering an explosive mixture under pressure connected with said charging port, and means actuated by and during the descent of the weight for successively opening said ports.

2. In combination, a weight and an explosive engine having the piston thereof connected to the weight and adapted to lift the same through variable distances, the cylinder of said engine being provided with an exhaust port, a scavenger port and a charging port, means for delivering air under pressure connected with the scavenger port, means for delivering an explosive mixture under pressure connected with the charging port, and means actuated through and during descent of the weight for successively opening said ports.

3. In combination, a weight and an explosive engine having the piston thereof connected to the weight and adapted to lift the same through variable distances, the cylinder of said engine being provided with an exhaust port, a scavenger port and a charging port, means for delivering air under pressure connected with the scavenger port, means for delivering an explosive mixture under pressure connected with the charging port, means actuated through and during descent of the weight for successively opening said ports, and means for retarding action of said opening means at the moment of opening the charging port to permit com-

- pletion of exhaust and scavenging before admission of explosive mixture.
4. In combination, a weight and an explosive engine having the piston thereof connected to the weight and adapted to lift the same through variable distances, the cylinder of said engine being provided with an exhaust port, a scavenger port and a charging port, means for delivering air under pressure connected with the scavenger port, means for delivering an explosive mixture under pressure connected with the charging port, an oscillating closure, and means actuated through and during descent of the weight to oscillate said closure.
5. In combination, a weight and an explosive engine having the piston thereof connected to the weight and adapted to lift the same through variable distances, the cylinder of said engine being provided with an exhaust port and with a charging port, means operative in conjunction with the engine piston for compressing an explosive mixture having connection with said charging port, and means actuated by and during the descent of the weight for successively opening and closing said ports in relatively timed order to effect exhaust and charging of the engine cylinder during each return stroke of the piston.
6. In combination, a weight and an explosive engine having the piston thereof connected to the weight and adapted to lift the same through variable distances, the cylinder of said engine being provided with exhaust, scavenging and charging ports, an air-supply chamber connected with the scavenging port, an explosive mixture chamber connected with the charging port, means operative in conjunction with the engine piston for drawing in and compressing air and explosive mixture in their respective chambers, and means actuated by and during the descent of the weight for successively opening and closing said ports in relatively timed order to effect exhaust, scavenging and charging of the engine cylinder during each return stroke of the piston.
7. In combination, a weight and an explosive engine having the piston thereof connected to the weight and adapted to lift the same through variable distances, the cylinder of said engine being provided with exhaust, scavenging and charging ports, an air-supply chamber connected with the scavenging port, an explosive mixture chamber connected with the charging port, a closed auxiliary cylinder and piston therein connected with the engine piston, valved connections between said auxiliary cylinder and each of said chambers such that the up stroke of the piston will draw in air and compress the contents of the explosive-mixture chamber, the down stroke compressing air in the scavenging chamber and drawing in the explosive mixture from the carburetor.

air in the scavenging chamber and drawing in the explosive mixture from the carburetor, and means actuated by and during the descent of the weight for successively opening and closing said ports in relatively timed order to effect exhaust, scavenging and charging of the engine cylinder during each return stroke of the piston.

8. In combination, a weight and an explosive engine having the piston thereof connected to the weight and adapted to lift the same through variable distances, the cylinder of said engine being provided with exhaust, scavenging and charging ports, an air-supply chamber connected with the scavenging port, an explosive mixture chamber connected with the charging port, a closed auxiliary cylinder and piston therein connected with the engine piston, valved connections between said auxiliary cylinder and each of said chambers such that the up stroke of the piston will draw in air and compress the contents of the explosive-mixture chamber, the down stroke compressing air in the scavenging chamber and drawing in the explosive mixture from the carburetor.

9. In combination, a weight and an explosive engine having the piston thereof connected to the weight and adapted to lift the same through variable distances, the cylinder of said engine being provided with exhaust, scavenging and charging ports, an air-supply chamber connected with the scavenging port, an explosive mixture chamber connected with the charging port, a closed auxiliary cylinder and piston therein connected with the engine piston, valved connections between said auxiliary cylinder and each of said chambers such that the up stroke of the piston will draw in air and compress the contents of the explosive-mixture chamber, the down stroke compressing air in the scavenging chamber and drawing in the explosive mixture from the carburetor, and said connections including ports provided in the auxiliary cylinder spaced from the top and bottom walls thereof respectively to provide in conjunction with said auxiliary piston air-cushioning means to limit the engine stroke in both directions.

10. In combination, a weight and an explosive engine having the piston thereof connected to the weight and adapted to lift the same through variable distances, the cylinder of said engine being provided with an exhaust port and a charging port, means for delivering an explosive mixture under pressure connected with the charging port, means actuated by and during the descent of the weight for successively opening said ports, and air cushioning means to limit the engine stroke in both directions.

11. In combination, a weight and an explosive engine having the piston thereof

- connected to the weight and adapted to lift the same variable distances, the cylinder of said engine being provided with an exhaust port and with a charging port, an explosive mixture chamber connected with the charging port, valved connections opening from said chamber into the engine cylinder, means associated with said chamber and connected with the engine piston to effect compression of the mixture in said chamber at each outward stroke of the engine piston and to draw in mixture from the carburetor at each return stroke, and means actuated by and during the descent of the weight for successively opening and closing said ports in relatively timed order to effect exhaust and charging of the engine cylinder during each return stroke of the piston.
12. In combination, a weight and an explosive engine having the piston thereof connected to the weight and adapted to lift the same through variable distances, the cylinder of said engine being provided in the floor thereof with a series of ports for exhausting, scavenging and charging the cylinder, a member having spaced open and closed portions, the closed portions resting upon said floor and adapted to close said ports, and means for rotating said member to open successively said ports.
13. In combination, a weight and an explosive engine having the piston thereof connected to the weight and adapted to lift the same through variable distances, the cylinder of said engine being provided in the floor thereof with a series of ports for exhausting, scavenging and charging the cylinder, a disk having openings therein and resting upon said floor so that the solid portions thereof are over said ports, and means actuated through and during descent of the weight for oscillating said closure to cause the same to open and close said ports successively.
14. In combination, a weight and an explosive engine having the piston thereof connected to the weight and adapted to lift the same through variable distances, the cylinder of said engine being provided in the floor thereof with a series of ports for exhausting, scavenging and charging the cylinder, a hollow member extending within the engine cylinder and having portions thereof resting upon said floor over said ports, means actuated through and during the descent of the weight for operating said member to cause the same to open and close the ports successively, and means for injecting a cooling liquid within the cavity of said member.
15. In combination, a weight and an explosive engine having the piston thereof connected to the weight and adapted to lift the same through variable distances, the cylinder of said engine being provided with a plurality of ports for operating the same, a single valve closure within said cylinder for opening and closing all of said ports in successively timed relation, and means actuated through and during descent of the weight for operating said closure.
16. In combination, a weight and an explosive engine having the piston thereof connected to the weight and adapted to lift the same through variable distances, the cylinder of said engine being provided with a plurality of ports for operating the same, a single valve closure for opening and closing all of said ports in successively timed relation, a pump having the piston thereof connected with said weight, and means actuated by fluid compression in the pump for operating said valve closure.
17. In combination, a weight and an explosive engine having the piston thereof connected to the weight and adapted to lift the same through variable distances, the cylinder of said engine being provided in the floor thereof with a series of ports for operating the same, a single disk closure resting over said ports and provided with a stem extending without said cylinder, a pump having the piston thereof connected with said weight, an auxiliary cylinder opening into the pump cylinder, and a piston working in said auxiliary cylinder and having connection with said closure stem, whereby descent of the weight and the pump piston will oscillate said disk and cause the same to open and close said ports successively.
18. In combination, a weight and an explosive engine having the piston thereof connected to the weight and adapted to lift the same through variable distances, the cylinder of said engine being provided in the floor thereof with a series of ports for operating the same, a pump having the piston thereof connected with said weight, means connected with the cylinder of the pump for adapting the same to cause the pumping piston to generate a predetermined pressure on the fluid within the pumping cylinder without regard to back pressure from the storage tank with which the pump is connected, and means operated by the pressure of the fluid in said pump generated by the descent of said piston and weight for opening and closing said ports in successively timed relation.
19. In combination, a weight and an explosive engine having the piston thereof connected to the weight and adapted to lift the same through variable distances, the cylinder of said engine being provided in the floor thereof with a series of ports for operating the same, a single disk closure resting over said ports and provided with a stem extending without said cylinder, a pump having the piston thereof connected with said weight, and means actuated by fluid compression in the pump for operating said valve closure.

- with said weight, an auxiliary cylinder opening into the pump cylinder through an annular series of ports centrally positioned on said auxiliary cylinder and a single port spaced therefrom, a valve for closing said single port to the extent desired, a piston working in said auxiliary cylinder having connection with said closure stem and a ring piston working in said cylinder and connected with said last named piston, whereby descent of the pump piston will force the fluid compressed thereby through said annular ports and said single port to cause the auxiliary piston to oscillate said disk, said ring piston operating to check the movement thereof when it comes opposite said annular ports.
20. In combination, a weight and an explosive engine having the piston thereof connected to the weight and adapted to lift the same through variable distances, the cylinder of said engine being provided with an exhaust port and with a charging port opening through the bottom of said cylinder, an oscillating closure having wings normally covering said ports, the wing over the charging port being wider than the wing over the exhaust port so that the exhaust port will be opened in advance of the charging port, and means for oscillating said closure.
21. In combination, a weight and an explosive engine having the piston thereof connected to the weight and adapted to lift the same through variable distances, the cylinder of said engine being provided with a series of ports for operating the same, a single oscillating closure for all of said ports, a pump having the piston thereof connected with said weight, an auxiliary cylinder having connection with the pump cylinder, a piston in said auxiliary cylinder operable by the fluid compressed in the pumping cylinder, and means connecting said piston with the closure so that movement of said piston in outward direction only will oscillate said closure in both directions to open and close said ports successively.
22. In combination, a weight and an explosive engine having the piston thereof connected to the weight and adapted to lift the same through variable distances, a pivoted member provided with means for closing a circuit to effect ignition in the cylinder, and means having connection with said weight and piston operating during ascent thereof to actuate said pivoted member to close said circuit.
23. In combination, a weight and an explosive engine having the piston thereof connected to the weight and adapted to lift the same through variable distances, a pivoted member provided with means for closing a circuit to effect ignition in the cylinder, a friction wheel engaging said pivoted member, a friction strip connected with the weight and engine cylinder and engaging said wheel, and means limiting movement of said member in one direction, whereby upward movement of the friction strip will operate said pivoted member to cause the same to close the circuit.
24. In combination, a weight and an explosive engine having the piston thereof connected to the weight and adapted to lift the same through variable distances, a pivoted arm having at the end thereof a switch member in the ignition circuit of the engine, an adjustable contact with which said switch is adapted to coöperate to close said circuit, and means having connection with said weight and piston operating during ascent thereof only to swing said arm on its pivot and close said circuit.
25. In combination, a weight and a two cycle explosive engine having the piston thereof connected to the weight and adapted to lift the same through variable distances, an ignition system, a valve system, means operated through and during the descent of said weight for operating said valve system, and means for operating the ignition during the active stroke.
26. In combination, a weight and a two cycle explosive engine having the piston thereof connected to the weight and adapted to lift the same through variable distances, a pump having the piston thereof connected with the weight, an ignition system, a valve system, means operated by the pressure of fluid within the pump for actuating the valve system, and means operated by the active stroke for operating the ignition system.
27. In combination, a weight and a two cycle explosive engine having the piston thereof connected to the weight and adapted to lift the same through variable distances, an ignition system, a valve system, and means for operating the same, a pump operated by said engine, a storage receptacle of the pump; and means having connection with said weight for operating said ignition system, and means governed by the condition of the fluid in the storage receptacle of the pump for automatically stopping and restarting said engine.
28. In combination, a weight and an explosive engine having the piston thereof connected to the weight and adapted to lift the same through variable distances, a pump having the piston thereof connected with said weight, a storage tank for receiving the pumped fluid, and means governed by the condition of the fluid in said storage tank for automatically stopping and restarting said engine.
29. In combination, a weight and an explosive engine having the piston thereof connected to the weight and adapted to lift

the same through variable distances, a pump operatively connected with said weight operating member, a lever system having a fixed fulcrum pivotally connected with said weight operating member and adapted to hold said weight operating member suspended and the engine inactive in one position thereof, a storage tank for receiving the pumped fluid, and means governed by the

condition of the fluid in said tank for controlling said lever system.

In testimony whereof I affix my signature in presence of two witnesses.

KENNEDY DOUGAN.
